[57] CLAIM

The ornamental design for a pager carrying case, as shown and described.

DESCRIPTION

FIG. 1 is a front perspective view of a pager carrying case showing our new design, with the flap in an open position;

FIG. 2 is a rear perspective view thereof;

FIG. 3 is a front elevational view thereof, with the flap in a closed position;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a top plan view thereof.

The phantom line showing of a pager in FIG. 2 is for illustrative purposes only, and forms no part of the claimed design.

The fabric texture of the case body is shown in fragmentary form in the figures for convenience of illustration, and should be understood as covering the entire body of the case.
